Des. 215,857

Patented Nov. 4, 1969

215,857

COMBINED ROTATABLE STYLING TRAY AND SUPPORT STAND THEREFOR

Leslie W. Olson, 1645 S. Ivanhoe,
Denver, Colo. 80222

Filed Mar. 20, 1968, Ser. No. 11,061

Term of patent 14 years

Int. Cl. D6—01

U.S. Cl. D33—3

FIG. 4

FIG. 5

FIG. 6

FIGURE 1 is a perspective view of the combined rotatable styling tray and support stand therefor showing my new design;

FIGURE 2 is a front elevational view;

FIGURE 3 is a rear elevational view;

FIGURE 4 is a top plan view;

FIGURE 5 is a bottom plan view; and

FIGURE 6 is a side elevational view thereof.

I claim:

The ornamental design for a combined rotatable styling tray and support stand therefor, as shown.
